UNITED STATES PATENT OFFICE

158,523

GAME TABLE TOP

Wendell H. Smith and George W. Conley, Mishawaka, Ind., assignors to United States Rubber Company, New York, N. Y., a corporation of New Jersey

Application May 7, 1947, Serial No. 138,890

Term of patent 14 years
(Cl. D33—14)

To all whom it may concern:

Be it known that we, Wendell H. Smith and George W. Conley, citizens of the United States of America, residing in Mishawaka, county of Saint Joseph, and State of Indiana, respectively, have invented a new, original, and ornamental Design for a Game Table Top, of which the following is a specification, reference being had to the accompanying drawing, forming part thereof, wherein:

Fig. 1 is a top plan view of a game table top, showing our new design and Fig. 2 is an end view.

We claim:

The ornamental design for a game table top, as shown.

WENDELL H. SMITH.
GEORGE W. CONLEY.
